UNITED STATES PATENT OFFICE.

WILLIAM D. PAYNE, OF WASHINGTON, DISTRICT OF COLUMBIA.

ILLUSION DEVICE.

Application filed April 2, 1925. Serial No. 20,260.

My invention relates to illusion devices and more particularly to devices which simulate the appearance of a coal fire in an open grate without the presence of burning coals.

There is a demand for illusion devices of the character specified for use in dwellings and other buildings in which it is desired, for one reason or another, to dispense with an actual coal fire while retaining the agreeable visual attributes of such a fire. The object of my invention is to provide such a device in a simple and economical but effective form.

Broadly, my invention consists in furnishing fire places, coal fire stoves or other heating units employing coal, whether existing or specially designed for the purpose, with one or more gas, electric, or other lighting elements, and interposing between the lighting elements and all positions from which they would ordinarily be observed a screen of transparent or semi-transparent material such as mica or glass, the said screen being tinted in such a manner that the transmitted light approximates the varying colors of a coal fire, and the screen, moreover, being subdivided by strips of relatively opaque material into a number of small panels or windows of various sizes and shapes approximating the shapes and sizes of the coals making up a bed of coals.

In the accompanying drawings I have illustrated one form which my invention may take.

Fig. 1 being a perspective view of a coal fire grate of the basket type as modified by my invention and inserted in a fire place of ordinary construction, the latter being only partially shown;

Fig. 2, a transverse central vertical section of the same;

Fig. 3 a broken, detailed view on an enlarged scale of frame elements for holding the transparent or semi-transparent panels; and

Fig. 4 a broken detail of a portion of the assembled screen.

Referring more particularly to the drawings, 1 indicates a fire place of the usual construction, 2—2 are supporting legs for a coal fire grate of the basket type made up of longitudinal grate bars 3—3 having upturned ends and transverse grate bars 4 of which one is shown. As shown, the legs 2 are united at the top by means of a rectangular frame 5 to which the ends of the grate

bars 3 are secured. However, the details of the grate construction are not essential to my invention, the example shown serving to illustrate the adaptation to the uses of my invention of an already existing coal fire grate.

The form of illuminating element shown in the illustrative embodiment of my invention is a gas burner 6 of ordinary construction, supplied by a gas pipe 7, which is provided with a valve 8.

9 and 10 indicate upper and lower frames, which are preferably duplicates of one another. The panels enclosed by the frames 70 are crossed by interlacing strips or bars 11, which are of irregular or tortuous shapes and which are joined to one another to break up the main panel into a number of smaller panels or windows of varying sizes and 75 shapes. The shapes of the small panels should be made to approximate, as nearly as possible in plane, the shapes and sizes of lumps of coal.

The pattern of the interlacing strips of 80 the upper frame 9 should be substantially duplicated in the pattern of the lower frame 10 so that when the two frames are superimposed the strips 11 of the upper frame will overlie and register with the strips of 85 the lower frame.

In the illustrative embodiment shown the transparent or translucent members comprise irregularly shaped panes of mica 12, 12 corresponding in size and shape to the 90 panels formed by the strips 11. As shown in Fig. 2 the panes 12 overlap at their edges and are clamped between the frames 9, 10, the frames being held together by any suitable means such as bolts 13, 13. The panes 95 12 of the mica, which are of suitable material, should be tinted in such a manner as to give to the light passing through the panes from the lighting element 6 the color of burning coals. To enhance the illusion 100 the panes should not be uniformly tinted but varying colors should be given to the panes in different regions of the frame in order to simulate corresponding differences in appearance of a burning fire. For example, the relatively dark spots which are frequently found in a coal fire should be represented in the screen of my invention by relatively dark colored and less transparent panels, which will give dark spots on the 110 screen, and similarly the tinting of other panes should be varied so as to give the illu-

sion of burning coals of varying intensities of illumination from dull red to yellow or even white.

While the screen enclosed by the frames 9 and 10 may be sufficient to create the desired illusion, the effect may be improved, if desired, by using additional screens. The front of the grate may be covered by a vertical screen made up in the manner heretofore described of frames 13 and 14, strips 11, and transparent or translucent panes 12.

The word "translucent" as used in the following claims is intended to cover any degree of translucency, including transparency.

It will be readily understood that changes of detail may be made within the scope of my invention, as broadly disclosed above, and I do not wish to be limited to the con-

struction shown, except as required by the following claims.

I claim:

1. An illusion device comprising in combination, a source of light, a translucent screen tinted to give to light transmitted therethrough the color of burning coals, and a network of relatively opaque material superposed upon said translucent screen, said network being composed of irregularly shaped intersecting strips outlining a variety of irregularly shaped panels simulating in profile lumps of coal.

2. An illusion device as claimed in claim 1, in which the panes are variously colored to simulate the variations in color of different portions of a coal fire.

WILLIAM D. PAYNE.
